KEY LOCKING MECHANISM

Edward B. Johnson, Grand Rapids, Mich.

Application July 18, 1945, Serial No. 605,677

5 Claims. (Cl. 235—130)

1

This invention relates to key locking mechanisms and more particularly to mechanisms for locking a partially depressed key of a calculating machine in that position whereby the operator by observation may detect the location of the partially depressed key and rectify any error caused thereby.

In the operation of calculating machines, the operator will sometimes only partially depress a key thinking that this key was fully depressed to register in the machine. When this occurs the key returns to normal and the operator is therefore not conscious of the error. There is thus no means of identifying where the error occurred.

It is the primary purpose of the present invention to provide a locking mechanism for the keys of a calculating machine whereby when a key is only partially depressed, insufficient to register in the machine, the partially depressed key is held in the depressed position allowing the operator to observe the location of the key wherein the error occurred.

Another purpose of the present invention is to provide a key locking mechanism whereby the partially depressed key must be fully depressed to register in the machine before it will return to normal position level with the other keys of the keyboard.

An illustrative embodiment of the invention is shown in the accompanying drawings, in which:

Fig. 1 is a vertical sectional view through the keyboard of a calculating machine showing a group of keys, one of which is partially depressed and locked in that position;

Fig. 2 is a vertical sectional view through the keyboard on line 2—2 of Fig. 1;

Fig. 3 is a horizontal sectional view taken along line 3—3 of Fig. 4;

Fig. 4 is a view similar to Fig. 1 showing one of the keys further depressed;

Fig. 5 is a similar view showing the key fully depressed for proper registration in the machine;

Fig. 6 is a similar view showing the position of the operating parts as the key is returning to normal position; and

Fig. 7 is a similar view showing the key as it approaches rest or normal position.

Referring then to the drawings in which like parts of the mechanism are designated by the same numerals in the several views, a calculating machine is provided with a key plate 10 and with a key guide plate 11 in relative spaced and parallel relationship, which guide plate receives in openings 14 for vertical sliding movement, the shanks 12 of the keys 13.

2

Means, not shown, are incorporated into the calculating machine which yieldably hold all the keys in normal extended position above the keyboard and brackets 15 are secured to the underside of the key plate 10 through which the spaced rods 16 extend.

The key locking mechanisms are all identical; therefore only one will be described. A latch block 17, having ears 18 and 19 and a latch dog 20 forming an integral part thereof, is slidably mounted on rods 16 and a spring 21 is connected between one of the brackets 15 and the ear 18 tending to move the latch block away from the shank 12 of the key. A notch 22 in the shank 12 of key 13 latches over the latch dog 20 to prevent a partially depressed key from returning to normal.

A bell crank lever 23, having legs 24 and 25, is pivotally mounted in the bracket 15 and tension spring 26 is connected to the outer end of leg 24 and to bracket 15 tending to move lever 23 in a clockwise direction. A spring 29 extending between the outer end of leg 24 of the bell crank lever and a bracket 30 attached to the key guide plate tends to move the bell crank lever in a counterclockwise direction. Tension spring 27 is attached at one end to the outer end of lever 25 and at the other end to ear 19 of the latching block 17 which tends somewhat to pull the latching block toward the notched side of the key.

In normal rest position, spring 21 has a greater pull on the latching block 17 than does the spring 27, causing latch block 17 to move away from the key shank 12. Also, the springs 26, 27 and 29 balance to hold the bell crank lever in the normal position as shown in the two outer positions in Fig. 1.

The lug 28 is secured to the shank 12 of the key 13 and when the key is depressed the lug controls the leg 24, moving bell crank 23 in a counterclockwise direction. When this occurs, the pull of spring 27 on the latch block 17 becomes greater than the pull of spring 21 thus moving the latch block toward the key shank causing the latch dog 20 to hook into notch 22, thus preventing the key from returning to normal position.

Operation

In normal position, the keys of a calculating machine are all flush and in extended position above the keyboard as shown in the two outer positions in Fig. 1. Should the operator only partially depress a key—which movement is not sufficient to register in the machine—the key will

be locked in this partially depressed position as shown in the center position in Fig. 1.

In moving from normal position to such partially depressed position, the lug 28 makes contact with leg 24 of the bell crank lever and moves it in a counterclockwise direction. This rotation of the bell crank lever causes the tension on spring 27 to become greater than the tension on spring 21; thus causing latching block 17 to move to the right whereby the latch dog 20 will hook into notch 22 in the key shank 12. In this hooked position, the number of the key will not have registered and this key will therefore remain partially depressed until it is fully depressed to register the number and thereafter be released to move to normal position.

In depressing the key from partially depressed locked position to fully depressed position and return to normal position, the mechanism moves to the various positions as shown in Figs. 4, 5, 6 and 7.

In Fig. 4, the key is moving downwardly and lug 28 is holding bell crank lever 23 in its rotated position with the leg 24 about to snap free of the influence of lug 28. In this position, the spring 27 is still pulling latch dog 20 against the notched side of the key shank 12.

In Fig. 5, the key is fully depressed to register the number in the calculating machine with the bell crank lever free from lug 28 and the springs 26, 27 and 29 balancing to hold the bell crank in normal position. The tension of spring 27 on the latch block 17 has become less than the tension of spring 21 whereby the latch dog 20 has moved to the left out of contact with the key shank 12.

In Fig. 6, the key is returning upwardly toward normal position and lug 28 has moved bell crank lever in a clockwise direction so that it may move past the leg 24 whereas in Fig. 7 the key has raised to a position where the leg 24 of bell crank lever 23 is about to move free of the lug 28 after which the parts move to normal or rest position as shown in Fig. 1.

It will thus be seen that the key locking mechanism for calculating machines herein shown and described is adapted to hold down a partially depressed key until it is fully depressed for registration in the machine, thereby informing the operator of the location of the partially depressed key and allowing the operator to rectify the error.

It will be understood that while but one specific embodiment of the invention has been herein shown and described, certain details of the construction shown may be altered or omitted without departing from the spirit of the invention as the same is defined in the appended claims.

I claim:

1. In a machine provided with a key having a shank, the key adapted to register numerical data on full depression thereof, the combination of latch means on the shank, a movable latch means adapted to engage the shank latch means to hold the key in partially depressed position and normally held yieldable out of engagement

with the shank latch means, means for yieldably moving said movable latch means into engagement with the shank latch means on partial depression of the key and means for rendering the last mentioned yieldable latch moving means ineffective on full depression of the key.

2. In a machine provided with a key having a shank, the key adapted to register numerical data on full depression thereof, a notch in the shank, a latch dog movable into the notch to hold the key in partially depressed position, means for yieldably holding the dog out of engagement with the notch in the shank, means for yieldably moving the dog into the notch on partial depression of the key and means for preventing the dog from entering the notch after full depression of the key.

3. In a machine provided with a key having a shank, the key adapted to register numerical data on full depression thereof, a notch in the shank, a latch dog movably mounted to engage the notch in the shank on partial depression of the key, means for yieldably moving the dog into the notch on partial depression of the key, a lever pivotally mounted adjacent the shank opposite the latch dog, yieldable means extending between the lever and the movable dog, a lug on the shank adapted to coat with the lever, said lug engaging the lever on partial depression of the key thereby increasing the effectiveness of the second yielding means and the lever moving free of the lug on full depression of the key.

4. In a machine provided with a key adapted to register numerical data on full depression thereof, the key having a shank, the combination of a notch in the side of the shank, a latch dog movable into and out of the notch, means for yieldably holding the dog out of engagement with the notch, a bell crank pivotally mounted adjacent the shank and on the side opposite the dog, the shank having a lug extending outwardly therefrom, said bell crank having a normally horizontal leg extending into the downward path of the lug, yieldable means for holding this leg of the lever in the path of the lug rotating the bell crank upwardly, the bell crank having a normal vertical leg, yieldable means extending between the vertical leg and the latch dog.

5. A construction as described in claim 4 in which the lug is located on the shank to engage and rotate the horizontal leg of the bell crank on partial depression of the key and located to free the bell crank on full depression of the key.

EDWARD B. JOHNSON.
